TOP COMB SYSTEM

Frank L. Crockett, Tenants Harbor, Maine, assignor to Whitin Machine Works, Whitinsville, Mass., a corporation of Massachusetts

Original application October 2, 1940, Serial No. 359,385, now Patent No. 2,353,812, dated July 18, 1944. Divided and this application August 13, 1942, Serial No. 454,749

11 Claims. (Cl. 19—116)

1

The invention relates to Heilmann type combers, being a division of my application, Serial No. 359,385, filed October 2, 1940, Patent No. 2,353,812 to which reference may be had for any matter herein shown but not described.

The object of the present invention is to improve the supporting and control means, the operation and the convenience of use of the top combs in combers of the kind referred to.

In the accompanying drawings Fig. 1 is a general cross-section through a combber to which the invention is applied; Fig. 2 a front elevation of one of the combing heads thereof; Fig. 3 a cross section of Fig. 2 in a plane adjacent to one of the top comb arms, showing the top comb in section; and Fig. 4 is a top plan of Fig. 2 showing also parts of the drive head.

It will be understood that in such a combber there are ordinarily several combing heads of which the operating parts are driven from the drive-head, at the end of the machine, by means of longitudinal shafts extending through all of the combing heads, and journaled on vertical frame uprights 1 located between the heads. One of these shafts operates the top comb system of this invention.

The dotted circle at the top of Fig. 1 represents a roll of cotton lap to be combed although the invention is not limited to cotton. This roll is supported on creel-rollers 2 and 3 appropriately driven so as to unwind the lap and deliver it over the lap plate 4 to the nipper feed roller 5 carried on the swinging nipper frame 25. The creel-rollers are carried respectively on through shafts 6 and 7, and driven step-by-step from the drive-head. By the feed roller 5 the lap is delivered to the nipper jaws 8 and 9 of which the lower jaw, or cushion plate, is fixed on the nipper frame which is mounted or hung so as to be movable toward and from the detaching mechanism. The other jaw, or nipper knife 9, opens to receive the lap fed by roller 5 and then closes upon it and nips it, holding the projecting end thereof in the path of the comb teeth on the comb cylinder 10 whereby the forward ends of the lap fibers are combed. After such forward ends have been thus cylinder-combed, the nipper jaws 8 and 9 moving forwardly, deliver the terminal tuft of combed fibers to the detaching mechanism, opening at the same time, so that the tuft may be drawn away from the body of the lap.

The detaching mechanism includes a pair of back rollers 11 and 12 which seize the front ends of the combber fibers presented to them by the nippers, and by their forward rotation separate

the tuft from the lap still held by the feed roller 5 and pull it through the teeth of the top comb 13 which has been lowered for that purpose. The top-comb combs the tail ends of the fibers constituting the tuft as they are drawn forward by the detaching rollers.

The detaching rollers receive the front end of the tuft on top of the tail end of the preceding tuft, with an appropriate overlap, thus piecing 10 the tufts together to form a continuous fleece composed of a succession of imbricated tufts. For this purpose the rollers are given an alternate forward and backward rotation, referred to as the piecing motion. In their forward motion they detach the tuft, as just stated and in their backward motion they return and expose a considerable length of the rear ends of the fibers in position to be overlapped by the next-arriving tuft. Ordinarily, also the axis of the top roll 11 is traversed forwardly and backwardly over the top of the bottom roll 12, in synchronism with the intermittent rotation, so as to facilitate the overlapping process. Its two extreme positions are indicated in the drawings.

25 The top comb system, shown best in Fig. 3, is automatically advanced and retracted with the nipper mechanism but with a different motion and through a different path. The comb proper 13 may be of usual construction but according to 30 this invention is mounted in a subframe 61 having at each end a stud 62 adapted to travel in and be guided by a specially curved slot 63 formed in the front part of a top comb arm 64. The subframe 61 is also link-connected to a rearward 35 pivot 66 on each top comb arm 64 by a link 65, the arrangement being such that the subframe and its top comb can be lifted and turned with respect to the arms and without lifting the latter, to the position indicated in dotted lines in 40 which the comb points forwardly and rests in a position where it can be easily inspected and cleaned. In this position the studs 62 rest in notches 63a at the tops of slots 63. The comb is quickly replaceable to its working position in 45 which the subframe rests by its studs 62 in the bottoms of the slots 63.

Each top comb arm is pivotally supported at the rear of the combber in the end of an upstanding crank arm 66a of the longitudinal top comb wag shaft 67, and each top comb arm has a track 68 by which it rests on a top comb roller 69, the latter being mounted in a fixed position on an appropriate adjustable bracket 70 on the part 41 carried on the adjacent frame work. The rollers 69 determine the position of the top comb arms

and top comb. As the top comb wag shaft 67 oscillates, the top comb receives a corresponding to and fro motion in the direction prescribed by the slope of the roller track 68, which is slight but sufficient to let the top comb descend, in its forward position, well into the tuft being drawn off by the detaching rolls. The to and fro motion given to the comb causes it to follow close behind the top detaching roller 11 as the latter makes its forward traverse (to assume its dotted line position). The top comb is shown in its high position in Fig. 1, the nipper jaws being still closed. This movement of the top comb is customary but is commonly imparted to it, in this type of comber, by the nipper frame itself or by connection to the detaching roll, whereas in the present case it is imparted to it by the wag shaft such as 67, at the rear of the comber and driven from the drive end of the comber.

It is sometimes desirable to impart a quick downward movement to the top comb so as to promote a positive penetration of its teeth into heavy lap. This quick drop is afforded in the present case by supplementary tracks adapted to engage the same rollers 69. Each of these tracks is in the form of a latch member, marked 71, adjustably pivoted at 70^a to a top comb arm and extended downwardly adjacent to the track 68 to be engaged by the roller 69. Each latch is held against swinging on its pivot in the forward stroke of the arm, by an adjustable stop 72, and the several parts are so arranged that on such forward stroke, the latch mounts and rides on the roller 69 until it drops abruptly off of its front side, thus giving the quick drop to the comb 13. On the return movement, the latch swings on its pivot dragging over the roller so that the top comb rests on tracks 68 and recedes in a path lower than that in which it advanced, combing the tail of the tuft at the same time, thus receiving a two-way motion for effectively combing the fibers.

Thus in the present case two tracks are provided at each side, one 68, to give a substantially straight line path and the other, 71, to give a high forward path and a low return. By turning each swinging track, 71, to an upright position it is of course rendered inoperative. Each track latch 71 is pivoted at 70^a on a plate 71^b which is adjustable on the top comb arm. The adjustment shown comprises in addition to the clamp bolt 71^c, three radially disposed bolts, screwed into the clamp plate as a hub, and bearing by their heads upon the edge of an aperture formed in the top comb arm. While other methods of adjustment of 70^a could be provided, this method is extremely delicate and at the same time permanent in its setting. It provides for adjustment in all directions as will be apparent. It will be observed also that the whole top comb structure can be swung completely out of the combing head by turning the arms over and back on the pivots of the cranks 66^a, this being a special virtue of the rearwardly located hinge support of the arms.

The drive of the top comb wag shaft 67 is indicated in Fig. 4 as taken from the nipper wag shaft 30 through a pair of segmental gears 73 and 74, but so far as this invention is concerned the means of driving it is of no consequence.

The principal parts of the combing machine in which the present invention is illustrated, but which are not directly related thereto, include the following: The drive-head mechanism comprising the gears 12^a, 15^a, 97, 98, 105, 106, 108,

109, 110, 120, 121, 122, 125, 126, 127 and 128; the creel system comprising the parts 33, 34, 44, 45, 46 and 49; the nipper system comprising the parts 25, 26, 27, 28, 29, 31, 32, 35, 37, 38, 39, 40, 41, 42, 54, 55, 56, 57 and 58; the scavenging system comprising the parts 21, 22 and 23; the detaching and piecing system comprising the parts 14, 15, 16, 75, 76, 77, 78, 79, 82, 83, 84, 85, 87, 87^a, 88, 89, 90, 90^a, 91, 92, 113, 113^a, 114, 115 and 119, and the delivery system comprising the parts 17, 18, 19, 20, 93, 94, 95 and 96.

I claim:

1. In a comber, a pair of top comb arms, a top comb subframe, links connecting it to said arms, stud-and-slot connections between said subframe and arms to guide the link-permitted movement of said subframe with respect to said arms, a top comb fixed to said subframe and means for oscillating said arms.

2. A top comb system comprising a top comb-supporting arm, an oscillating support therefor, another support therefor including a fixed top comb supporting stud, a track on the arm riding on said stud in the rearward stroke and a supplementary track on the arm riding on said stud in the forward stroke and adapted to fall off of it at the end of such stroke.

3. In a comber having a comb cylinder, a rear support located behind the cylinder, top comb arms hinged to said support and extending forwardly therefrom, means intermediate said support and the front of said arms for determining the position of the top comb with relation to the tuft, a subframe supported on the front ends of said arms, links connecting said subframe to the arms and stud and slot means between said subframe and arms prescribing the path of movement therefor when swinging on said links.

4. In a comber a pair of top comb arms, a top comb subframe, links connecting said subframe to the arms, stud-and-slot connections between said subframe and arms to guide the link-permitted movement of said subframe with respect to said arms and a top comb fixed to said subframe.

5. The combination in a comber having a swinging nipper system cooperating with a comb cylinder and detaching motion, of a pair of top comb arms having a top comb mounted for manual movement on the forward ends thereof, said top comb arms being pivotally supported on the machine independently of, and in rear of, said nipper system and extending forwardly above the same whereby they can be swung upwards and backwards relatively thereto, and being supported also on fixed means between their pivotal rear support and said top comb.

6. The combination in a comber, of its fiber-supply creel, nipper system, comb cylinder, and detaching mechanism, with a pair of top comb arms pivotally supported in rear of all said parts and extending forwardly over said creel and nipper system and capable of being swung on their pivotal axis upwards and backwards relatively thereto, a top comb, means for movably mounting said top comb on the forward ends of said arms, said means normally permitting the top comb to be turned thereon to a forward-pointing position and a member fixedly mounted on the machine frame constituting an intermediate support for said top comb arms.

7. The combination in a comber having a swinging nipper system cooperating with a comb cylinder and detaching motion, of a top comb mounted on the forward ends of a pair of top

comb arms, said arms having pivotal support on the machine independently of, and in rear of said swinging nipper system and extending forwardly over the same, and having intermediate supporting and guiding means, and means also independent of said nipper system for imparting to-and-fro motion to said top comb arms relatively to said supporting and guiding means.

8. The combination of claim 7 in which said supporting and guiding means comprise alternately-operating track members organized to guide the top comb through a high path of movement on its forward stroke and a lower path on its rearward stroke.

9. A top comb system for combers comprising a top comb, a pair of comb-supporting arms having the top comb located at their forward extremities, a hinge supporting the rear end of each arm, means for oscillating the hinge to impart to-and-fro motion to the arms and an additional

5 support for each arm located intermediate of said hinge and top comb and comprising two engaging structures, one of which is located on the machine frame and the other on the top comb arm, one of said structures comprising a stud member and the other comprising a track member to engage said stud member on the forward movement of the arm and a track member to engage said stud member on the backward movement of the arm so as to prescribe different paths for the forward and rearward strokes of the top comb.

10 10. The top comb system as defined in claim 9 in which said two track members are located on the top comb arm and the stud member is fixed on the machine frame.

15 11. The top comb system as defined in claim 9 having means for holding one of said track members out of operation.
